DESIGN FOR A TOY AEROPLANE HANGAR

Edgar L. Kuesthardt, Toledo, Ohio

Application February 24, 1934, Serial No. 50,851

Term of patent 7 years

To all whom it may concern:

Be it known that I, EDGAR L. KUESTHARDT, a citizen of the United States, and residing at Toledo, in the county of Lucas and State of Ohio, have invented a new, original, and ornamental Design for a Toy Aeroplane Hangar, of which the following is a specification, reference being had to the accompanying drawing forming a part thereof.

In the drawing:

Fig. 1 is a perspective view of a toy aeroplane hangar showing my design.

Fig. 2 is an end elevational view of the closed end opposite that shown in Fig. 1.

I claim:

The ornamental design for a toy aeroplane hangar substantially as shown.

EDGAR L. KUESTHARDT.
